CABINET OR SIMILAR ARTICLE

Carl W. Sundberg, Bloomfield Hills, Mich., assignor to Whirlpool Corporation, St. Joseph, Mich., a corporation of Delaware

Application April 19, 1957, Serial No. 45,801

Term of patent 14 years

(Cl. D33—19)

Figure 1 is a perspective view of a cabinet, or similar article, showing my new design;

The dotted lines indicating a wall are for illustrative purposes only.

The configuration of the back and upper compartments of the cabinet are substantially identical to the front thereof.

I claim:

The ornamental design for a cabinet or similar article, as shown and described.
